HARRY A. WRIGHT Inventor

By *Richard B. Owen* Attorney

Patented Dec. 15, 1925.

1,565,698

UNITED STATES PATENT OFFICE.

HARRY A. WRIGHT, OF HILLSBORO, OHIO.

CREAM-TESTING MACHINE.

Application filed October 8, 1921. Serial No. 506,476.

To all whom it may concern:

Be it known that I, HARRY A. WRIGHT, a citizen of the United States, residing at Hillsboro, in the county of Highland and 5 State of Ohio, have invented certain new and useful Improvements in Cream-Testing Machines, of which the following is a specification.

This invention relates to power operating mechanisms and more particularly to a 10 novel and improved mechanism, whereby energy may be communicated to produce rotary power in various types of apparatus.

The primary object of the invention resides in the construction of a power operating mechanism particularly designed for 15 communicating power to cream testing machines and centrifugal separators and the like by mechanical power, when electric or 20 water power cannot be readily obtained.

Another and very important object of the invention resides in the construction of a mechanical power operating mechanism, capable of being constructed of different 25 kinds of material and in various sizes and if so desired in the form of a toy, and one in which the parts are extremely simple in construction, easily assembled, highly efficient in operation, practical, durable and 30 otherwise capable of being manufactured at a very low cost, whereby its commercial possibilities are greatly enhanced.

The invention will be best understood from a consideration of the following 35 detailed description taken in connection with the accompanying drawing forming a part of this specification, with the understanding, however, that the invention is not confined to any strict conformity with the showing 40 in the drawing, but may be changed and modified so long as such changes and modifications mark no material departure from the salient features of the invention as expressed in the appended claims.

45 I attain the above objects and others by the accompanying drawings, wherein:

Figure 1 is a side view, showing the invention as applied for operating a cream testing apparatus.

50 Figure 2 is a plan view.

Figure 3 is a detail view of the cable reel and ratchet mechanism.

Figure 4 is a sectional view of the reel and ratchet shown in Figure 3; and

55 Figure 5 is a section taken on the line 5—5 of Figure 1.

Referring now to the drawings, wherein like reference characters designate corresponding parts throughout the several views, the supporting mechanism of the machine 60 comprises a rectangular frame 5, having supporting legs 6, 7 and longitudinal connecting bars 8, whereby a strong and rigid support is had for the operating mechanism 65 now to be described in detail.

Rigidly secured to one end of the frame I have provided a standard 9, which carries a pulley 10 at its upper end, about which a cable 11 is trained and connected to a weight 12. The opposite end of the cable 11 is wound on a reel 13 mounted on a shaft 14, journaled in suitable bearings 15 of the frame above referred to. A ratchet wheel 14' and a spring pressed pawl 15' secured to a toothed gear 16, mounted on the shaft 14 are also provided for communicating power through a pinion 17, rotatable with the shaft 18, which carries a large ratchet 19 outside the frame, as clearly shown by Figures 1 and 2 of the drawing. The teeth of the said ratchet 19 are engageable by an L-shaped spring or resilient member 21, secured to the frame and normally preventing rotation of the cable and reel thereon when the same is wound and the weight 12 is in its raised or elevated position. The spring 21 above referred to, is adapted to be raised or lifted by an arm 22, which is secured to a sliding member 23, operable in a guide 24 on the supporting frame of the structure. A pitman 25 connected at one end to the slide 23 and pivoted as at 26 to a crank wheel 27 communicates power to the horizontal shaft 28 from the ratchet 19. The shaft 28 is journaled in bearings 29 substantially intermediate the ends of the frame. The lifting arm 22 carries an actuating arm 22', which is disposed in the path of the teeth on the ratchet 19, which is adapted to operate the slide 23 when the ratchet wheel is released.

A pulley 30 rotatable with the shaft 28 is provided with a cross cable 31, trained about a horizontally positioned second pulley 32, mounted on the vertical shaft 33 which drives the mechanism within the centrifugal separator or tester, designated in its entirety by 35. The said tester is supported by the usual standard or braces 36 and preferably on the opposite end of the frame whereby power may be communicated 105 thereto through the mechanism above referred to.

A balance wheel 37, mounted on the opposite end of the shaft 28 permits of the rotation thereof, whereby the crank wheel 27 will reciprocate the slide 23 so that the 5 arm 22 may engage and lift the spring 21, whereupon the force of gravity acting on the weight 12 will cause rotation to the respective shafts 14, 18, and consequently drive the horizontal shaft 28 and the pulleys 30, 32 and thus communicate motion to the vertical shaft 33 whereby the centrifugal separator is operated. Of course, in machines of this type it is not necessary 10 for the centrifugal separator or tester to operate for a long duration of time and thus the cable may be easily rewound to its normal position when it is desired to make 15 a test or observe the effects on the milk within the container.

20 While I have shown and described the invention as directed to a milk tester or separator, it will be readily observed that the device readily lends itself to be constructed in the form of a toy and that the 25 vertical shaft 33 may drive any suitable member carried thereby, as is well understood.

In the accompanying drawings, I have 30 illustrated my invention embodied in one form by way of example, and which in practice has been found to be highly satisfactory in obtaining the desired results. It will be obvious however, that other embodiments may be adapted, and that various 35 changes in the details of construction may be resorted to by those skilled in the art without departing from the spirit and scope of the invention. It is furthermore understood that the invention is not necessarily 40 limited or restricted to the precise elements shown except in so far as such limitations are specified in the subject matter being claimed.

What I claim as new and desire to secure 45 by Letters Patent is:

1. An apparatus of the class described comprising a supporting frame, a vertical standard and pulley mounted thereon, said standard secured to the frame, a cable having 50 a weight attached to one end and wound over said pulley, a horizontal shaft and reel rotatable thereon for receiving the wound cable, ratchet and pawl mechanism for preventing retrograde movement of the 55 wound reel, a driven shaft and meshed gearing whereby the same may be operated by the reel, a spring held ratchet wheel supported on one end of the driven shaft, a reciprocating slide for releasing the holding 60 spring of said ratchet wheel, a power shaft

supported on the frame, a rotatable member secured to one end of the power shaft, a balance wheel mounted on the opposite end of said power shaft, a pitman pivoted at one end of the rotatable member and at its 65 opposite end to the slide, an operating arm carried by the slide and disposed in the path of the teeth on the spring held ratchet wheel, a pulley on the power shaft, a vertical shaft and pulley thereon supported on the frame, 70 and a cross cable trained about said pulleys whereby centrifugal force may be communicated to a member on said vertical shaft.

2. An apparatus of the class described comprising a frame, a standard and pulley 75 mounted thereon, said standard secured to the frame, a weighted cable trained on said pulley, a horizontal shaft and reel rotatable thereon for winding the cable, ratchet and pawl mechanisms for preventing retrograde 80 movement of the wound wheel, a driven shaft, gearing interposed between the respective shafts for driving the driven shaft, a spring held ratchet reel on the driven shaft, a reciprocating slide cooperating with the 85 spring held ratchet, a power shaft and a rotatable member carried thereby, a pitman connected at one end to the rotatable member and at its opposite end to the slide an operating member carried by the slide and 90 disposed in the path of the spring held ratchet wheel, and a vertical shaft mounted on the frame and means for operating said vertical shaft from the power shaft.

3. An apparatus of the class described 95 comprising a rectangular frame, a standard and pulley mounted thereon, said standard carried by the frame, a weighted cable trained over said pulley, a horizontal shaft and reel rotatable thereon for winding the 100 cable and means for preventing retrograde movement of said reel when wound, a driven shaft and means for driving said driven shaft from the reel, a ratchet wheel mounted on one end of the driven shaft, an L-shaped 105 resilient member for maintaining said ratchet wheel and prevent movement of the respective shafts, reciprocating means for engaging said L-shaped member to permit of the operation of said shafts, a power 110 shaft, means cooperating between said power shaft and reciprocating means, for operating the power shaft from the ratchet wheel, a vertical shaft, and a pulley and cable mechanism operatively connecting the power shaft 115 with the vertical shaft, whereby centrifugal force may be communicated to the vertical shaft.

In testimony whereof I affix my signature.
HARRY A. WRIGHT.
